UNITED STATES PATENT OFFICE

OSCAR SCHULTZ, OF HAMBURG, GERMANY

RUDDER ARRANGEMENT FOR SHIPS

Application filed March 3, 1930, Serial No. 432,876, and in Germany August 3, 1929.

This invention relates to a steering device, which enables an exchanging of the rudder to be easily effected. Similar arrangements are known, which enable the exchanging of the rudder without docking the vessel. These however are open to the objection that in the case of fracture of the rudder spindle the broken rudder can only be removed with difficulty which takes a considerable time, as the broken rudder must for example be withdrawn at the top. Moreover the inserting of the rudder when exchanging same is difficult. These disadvantages are overcome according to the invention in that a stern-wedge, removable towards the rear and connected with a locking device, is provided and moreover the stern steering wheel mounted on the rudder spindle has a slot over which, in the midship position of the rudder, the gap freed by the pulling out of the stern-wedge registers. Moreover the stern tube is open at the bottom and has extensions the edges of which extend obliquely in downward direction.

Owing to this arrangement it is possible, in the case of breakage of the spindle, to slide the rudder provided with suitable cut out portions along the inclined edge of the extensions until it comes into the midship position and then drops into the water by gravity.

An embodiment of the invention is illustrated by way of example in the accompanying drawings in which:

Fig. 1 shows the stern in vertical section, the removed stern-wedge and the auxiliary devices shown in side elevation.

Fig. 2 is a top plan view of the stern fitted with the rudder and the locking device.

Fig. 3 is a rear view of the stern tube with the rudder in operative position.

Fig. 4 is a side elevation of the driving mechanism, for the rudder.

Fig. 5 shows the stern tube in vertical cross section together with the rudder spindle.

The stern of the vessel is provided with a stern wedge *a* adapted to be pushed out towards the rear, this stern wedge having a rack *b*. The rack *b* meshes with a spur

wheel mounted on a rotatable disc *c*, the part of the stern wedge carrying the rack being preferably moved in a guide. The rotatable disc *c* has a notch *d*, in which a spring controlled lever *e* of a locking device *f* engages, which lever can be operated either directly by hand or indirectly mechanically. When opening the locking device, the stern wedge *a* can be brought into the position shown in Fig. 1 by turning the disc *c* so that a gap is formed designed to serve as passage for the rudder. The stern steering wheel *i* on the rudder spindle *g* has a slot *h* arranged so that it registers with the gap liberated by the stern wedge *a* when the rudder is in the midship position. The rudder spindle *g* has a finger *k* adapted to engage in a notch *l* in the stern steering wheel *i*. A chain drum *m* is provided, according to the invention, with a flange *n*, adapted to be arrested by means of a locking lever *o*. For this purpose the locking lever *o* is hingedly mounted and has a catch *p* which, when the lever *o* is thrown over and the steering wheel *g* is operated, slides on the drum flange *n* until it drops into a notch in the drum flange, corresponding to the midship position of the rudder. The connection between the chain drum *m* and the stern steering wheel *i* is effected by means of a chain *r*, known per se.

In order to avoid the losses from friction when steering, the lower open end of the stern tube *s* lying in the water has guide bars *t*. The stern tube has further tubular projections *u* open towards the rear, bordered with downwardly extending inclined edges, so that in the case of breakage of the rudder spindle, the rudder part situated in any rudder angle is positively guided with the upper edges of suitable cut out portions provided in the rudder back piece along the inclined upper edge of the projections *u* and falls out at the bottom from the stern tube. The exchanging of the upper part of the rudder spindle can be effected by means of a lifting tackle or elevator fitted on the mast. When exchanging the steering rudder, owing to breakage of any kind, more particularly a fracture of the

rudder spindle, the operation is as follows:

- After the lower portion of the rudder standing at any angle is positively guided, directly after the breakage of the rudder spindle, through the tubular projections, open towards the rear, it drops downward out of the stern tube. The lever *o* of the steering apparatus is then thrown over and the rudder brought into the midship position, this being positively effected in that the catch *p* of the lever *o* engages in the corresponding notch in the drum flange *n*, the slot *r* of the stern steering wheel at the same time registering above the stern wedge *a*. The locking device *f* is then opened in that the lever *e* is depressed with the foot or by means of a suitable device adapted to be operated by the helmsman. After having been unlocked the disc *c* is rotated, so that the stern wedge *a* with the rack *b* is pushed out of the hull of the ship to the rear by means of the spur wheel rigidly connected with the disc *c* (see Fig. 1 and the stern wedge shown in dot dash position in Fig. 2). After the pulling out of the stern wedge *a* a gap is formed in the stern, the slot *h* of the stern steering wheel *i* being situated above this gap, so that after the removal of the upper broken off portion of the rudder spindle, a spare rudder can be introduced. After the introduction of the new steering rudder, the disc *c* is turned back, the pushed out stern wedge *a* being thereby returned into its initial position. The lever *o* of the steering apparatus is then thrown off (see Fig. 4) and the vessel is again ready for travelling.

I claim:—

1. A rudder arrangement on ships in which the steering rudder can be exchanged while the vessel is floating, comprising in combination a stern wedge adapted to be pushed out towards the rear in forming a gap for the introduction of a fresh rudder, a locking device adapted to hold said stern wedge in the closing position, and a stern steering wheel mounted on the rudder tube having a slot adapted to register with the gap produced by the pushed out stern wedge when the rudder is in midship position.

2. A rudder arrangement as specified in claim 1, comprising in combination a chain drum, a locking lever adapted to lock said drum, a flange on said drum having a notch, and a catch on said lever adapted to slide on said flange and to engage in said notch when the rudder is in the midship position.

3. A rudder arrangement as specified in claim 1, comprising in combination with the stern wedge, a rack mounted on said stern wedge, a toothed wheel engaging in said rack, and a rotatable disc, carrying said toothed wheel.

4. A rudder arrangement as specified in claim 1, comprising in combination a ro-

tatable disc having a notch, and a spring controlled locking lever adapted to engage in said notch.

5. A rudder arrangement as specified in claim 1, comprising in combination with the rudder spindle, a stern tube open towards the rear adapted to receive said spindle, a guide bar in said stern tube adapted to reduce the friction of said spindle, tubular projections, open towards the rear arranged on the lower end of said tube in the water the upper edges of said projections inclined towards the rear adapted to positively guide in the event of a rudder spindle fracture the rudder part in standing at any angle by means of the inclined upper edges of cut out portions in the back of said rudder so that the rudder can fall out through the bottom end of said stern tube.

In testimony whereof I affix my signature.

OSCAR SCHULTZ.
